B. J. RYBIN

CHARGE FORMING DEVICE

Filed May 12, 1925

UNITED STATES PATENT OFFICE.

BLAHOSLAV JOHN RYBIN, OF BRIDGER, MONTANA, ASSIGNOR OF ONE-FOURTH TO
CLEMENT J. BALDWIN, OF BRIDGER, MONTANA.

CHARGE-FORMING DEVICE.

Application filed May 12, 1925. Serial No. 29,817.

This invention relates to a charge forming device for use on internal combustion engines and aims particularly to provide a device of this character especially designed and adapted to make it practicable to use crude oil or the heavier fractions of petroleum as a fuel for the engines of conventional types of tractors. The device constituting the present invention separates, pre-heats, conditions and vaporizes the usable content of the oil employed and preserves for other purposes the portion not susceptible of use as a fuel.

A further object of the invention resides in the provision of a charge forming device having these advantages and capacities and which is of simple and durable construction, reliable and effective in operation and adapted for convenient installation at a comparatively slight cost on conventional tractor engines.

A still further object resides in the provision of a device of the character specified which makes the engine on which it is employed susceptible of being run with little or no fuel cost, the oil preserved after the fuel content has been extracted having a sale value as a lubricant practically equal to the original cost of the crude oil or other oil employed.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view partly in elevation and partly in section showing the invention applied to the engine of a conventional tractor:

Figure 2 is a sectional view of the water control valve and atomizer;

Figure 3 is a view in section on line 3—3 of Figure 1.

Figure 4 is a fragmentary detail sectional view of a portion of the retort employed, and

Figure 5 is a fragmentary perspective view showing a variation in the manner of connecting the residue collecting reservoir to the retort.

Referring to the drawing the numeral 1 designates generally a tractor which is shown as being of the type of the "Ford-

son" tractor and which has an engine 2 provided with the usual exhaust manifold 3 from which an exhaust pipe 4 leads. The engine 2 is equipped with the usual water cooling system, a part of which is the usual 60 radiator 5. The usual intake manifold 6 is provided. A main air supply pipe 7 leads to the intake manifold 6. At the inlet end of the supply pipe 7 the usual air washer 8 is provided. A carburetor 9 is provided and may be supplied with crude oil from the main tank 10 or with gasoline for starting purposes from a tank 11, a single fuel line 12 connecting the fuel tanks 10 and 11 to the carburetor and the supply of one or the other fuel being regulated by means of a two-way valve 13. If desired the gasoline tank 11 may be omitted and a blow torch used to heat up the parts when starting.

An air tube 15 leads from the pipe 7 to a combined air and water supply pipe 16. A water or vapor supply tube 17 communicates at one end with the radiator 5 and at its other end with an atomizer 18 the latter being connected with pipe 16. Between the tube 17 and the atomizer 18 a two way valve 19 is interposed and may be adjusted to supply water to the atomizer 18, to shut off the water, or to drain the same. As shown in Fig. 2 the atomizer 18 has a transverse passage 20 with which the valve 19 communicates and a tapering longitudinal passage 21 communicating with the transverse passage 20 and terminating in a jet 22, the latter being located opposite the tube 15. A needle 90 valve 23 is threaded into the atomizer and regulates the amount of flow of water through the jet 22. The pipe 16 is connected to a terminal 24^a of a coil 24 located within the exhaust manifold 3 and having a terminal 24^b leading to the contact space of the carburetor 9. The outlet 25 of the carburetor leads to a retort 26 comprising an annular casing 27 having its inner wall encircling and snugly fitting the exhaust pipe and having its ends abutting flanges of the exhaust pipes. A partition 28 is provided in the casing 27 and defines a sinuous passage for the commingled air steam and entrained crude oil. A pipe 30 carries the vaporized and preheated mixture of oil, steam and water to the intake manifold. The lower end wall of the casing 27 is of trough like formation to collect the liquid or unvaporized oil precipitated by the parti-

tion or baffle 28 of the retort. From the lower end of the casing 27 a pipe 31 leads to a reservoir 32. A valve 33 is incorporated in the pipe 31 and retards the flow of the oil. As shown in Figure 3 the reservoir 32 is shaped to extend at least partially around the exhaust pipe 4 and has a drain plug 34. In operation the air and water supplied through pipe 16 are converted into mixed steam and highly heated air in the coil 24 and as such pass to the contact space of the carburetor where the crude oil is partly vaporized and entrained and carried into the retort 26 wherein all of the volatile content of the oil is completely vaporized and thoroughly commingled with the hot air and steam to form the combustible charge which is delivered through the pipe 30 to the intake manifold. The oil which does not vaporize collects in the bottom of the retort and passes down into the reservoir 32 wherein it is subjected to a prolonged heat treatment whereby any volatile products remaining are vaporized and pass back up the pipe 31 into the retort and subsequently into the engine. The oil which remains in the tank 32 is drained off through the plugged outlet 34 and used or sold as a lubricant. An auxiliary air control valve 50 is provided in the pipe 7 and is opened up after the engine has been thoroughly heated up.

In order to facilitate starting, the portion of the pipe 30 disposed between the outer wall of the annular casing 27 and the partition 28 has a small opening 30a provided therein as shown in Figure 4 so that a small amount of fuel may pass directly through the casing 27 from the carburetor to the pipe 30.

As shown in Figure 5 the valve 35 may be omitted and in lieu thereof, a bend 40 may be provided in the pipe, the bend constituting a trap. Also the pipe 31 may have a coil formed therein, the coil encircling the exhaust pipe and being made up of one or more turns. If instead of a coil the pipe 31 simply has a portion placed close up to and along the exhaust pipe, about 50% of the residue will be vaporized, whereas if a coil of one turn is used, a vaporization of 70% of the residue occurs. A coil of two turns results in the vaporization of 85% of the residue.

I claim:

1. In a charge forming device for use with internal combustion engines having a carburetor, means for mixing a supply of air and water, means for heating said mixture to highly heat the air thereof and convert the water thereof into steam, means for conveying the heated air and steam to the contact space of the carburetor to partially vaporize and entrain the fuel, a retort connected with the carburetor and designed to vaporize the volatile content of the oil and complete the formation of the combustible mixture, and means for conveying the combustible mixture to the engine.
2. In a charge forming device for use with internal combustion engines having a carburetor, means for mixing a supply of air and water, means for heating said mixture to highly heat the air thereof and convert the water thereof into steam, means for conveying the heated air and steam to the contact space of the carburetor to partially vaporize and entrain the fuel, a retort connected with the carburetor and designed to vaporize the volatile content of the oil and complete the formation of the combustible mixture, and means for conveying the combustible mixture to the engine, said retort having means to precipitate the non-volatile content of the oil, and a reservoir connected to the retort for receiving the oil from the retort.
3. In a charge forming device for use with internal combustion engines having a carburetor, means for mixing a supply of air and water, means for heating said mixture to highly heat the air thereof and convert the water thereof into steam, means for conveying the heated air and steam to the contact space of the carburetor to partially vaporize and entrain the fuel, a retort connected with the carburetor and designed to vaporize the volatile content of the oil and complete the formation of the combustible mixture, and means for conveying the combustible mixture to the engine, said retort having means to precipitate the non-volatile content of the oil, and a reservoir connected to the retort for receiving the oil from the retort.
4. In a charge forming device for use with internal combustion engines having a carburetor, means for mixing a supply of air and water, said means including an atomizer, means for heating said mixture to highly heat the air thereof and convert the water thereof into steam, means for conveying the heated air and steam to the contact space of the carburetor to partially vaporize and entrain the fuel, a retort connected with the carburetor and designed to vaporize the volatile content of the oil and complete the formation of the combustible mixture, and means for conveying the combustible mixture to the engine.
5. In a charge forming device for use with internal combustion engines having a carburetor, an intake manifold, an exhaust manifold, an exhaust pipe and a main air supply pipe, a combined air and water pipe, a connection between said pipe and the air supply pipe, an atomizer connected to said pipe, a two way valve control water supply pipe leading to the atomizer, a coil located within the exhaust manifold and connected to the combined air and water supply pipe and to the carburetor, a retort mounted on

the exhaust pipe and connected to the carburetor, and a connection between the retort and the intake manifold.

6. In a charge forming device for use with internal combustion engines having a carburetor, an intake manifold, an exhaust manifold, an exhaust pipe and a main air supply pipe, a combined air and water pipe, a connection between said pipe and the air supply pipe, an atomizer connected to said pipe, a two way valve control water supply pipe leading to the atomizer, a coil located within the exhaust manifold and connected to the combined air and water supply pipe and to the carburetor, a retort mounted on the exhaust pipe and connected to the carburetor, a connection between the retort and the intake manifold, a reservoir mounted on the exhaust pipe and a pipe between the retort and the reservoir.
7. In a charge forming device for use with internal combustion engines having a carburetor and an exhaust pipe, means for supplying a preheated gas to the carburetor to partially vaporize and entrain the fuel,
- 25

a retort connected to the carburetor and designed to completely vaporize the fuel and complete the formation of the mixture, said retort having means to precipitate the portion of the fuel not volatilized by the retort, a reservoir below the retort, and a trapped pipe between the reservoir and the retort, said pipe having a portion extended along the exhaust pipe.

8. In a charge forming device for use with internal combustion engines having a carburetor and an exhaust pipe, means for supplying a preheated gas to the carburetor to partially vaporize and entrain the fuel, a retort connected to the carburetor and designed to completely vaporize the fuel and complete the formation of the mixture, said retort having means to precipitate the portion of the fuel not volatilized by the retort, a reservoir below the retort, and a trapped pipe between the reservoir and the retort, said pipe having a coil extending around the exhaust pipe.

BLAHOSLAV JOHN RYBIN.
